BATHTUB

Horst Godfrey Bonsack, Flat 17, 51 South St.,
London, W.1, England

Filed Aug. 12, 1968, Ser. No. 13,102

Claims priority, application Great Britain Feb. 27, 1968

Term of patent 14 years

Int. Cl. D23—02

U.S. Cl. D23—55

FIG. 1.

FIG. 2.

FIG. 3.

FIG. 4.

FIG. 5.

FIG. 6.

FIG. 1 is a perspective view from above and one side of a bathtub showing my new design;

FIG. 2 is a side elevational view taken from the side opposite to the view shown in FIG. 1;

FIG. 3 is a top plan view thereof;

FIG. 4 is a bottom plan view thereof;

FIG. 5 is an elevational view taken from one end thereof; and

FIG. 6 is an elevational view taken from the end opposite to that shown in FIG. 5.

I claim:

The ornamental design for a bathtub, as shown.
